UNITED STATES PATENT OFFICE.

CHAUNCEY D. BAKER AND LEWIE G. BRONSON, OF CHICAGO, ILLINOIS.

ELECTRICAL APPARATUS.

SPECIFICATION forming part of Letters Patent No. 417,217, dated December 17, 1889.

Application filed April 30, 1888. Renewed August 8, 1889. Serial No. 320,141. (No model.)

To all whom it may concern:

Be it known that we, CHAUNCEY D. BAKER and LEWIE G. BRONSON, residing at Chicago, in the county of Cook and State of Illinois, 5 citizens of the United States, have invented a new and useful Improvement in Electric Apparatus, of which the following is a specification, reference being had to the accompanying drawings, in which—

10 Figure 1 is a side elevation, the armature being in the position which it occupies when the main circuit is open. Fig. 2 is a plan. Fig. 3 is a section at line *x* of Fig. 1, looking to the right. Fig. 4 is a side elevation 15 showing the armature in the position which it occupies when the main circuit is closed and the conditions are normal. Fig. 5 is a side elevation showing the position of the armature when the main circuit is closed and 20 the intensity of the current has been, from any cause, materially increased over its normal condition.

Our improvement is primarily designed to be used with relay-instruments—such as are 25 used in connection with burglar-alarms and other electrical devices—for the purpose of bringing into operation an independent set of electrical devices when there is a material derangement of or change in the current of 30 the main circuit. Such derangement or change may occur either as a consequence of the opening of the circuit, or by short-circuiting the main circuit or grounding part of it.

The leading object of our invention is to 35 construct a relay so that one magnet and one armature will do the work, which we accomplish by means of an armature composed of two parts hinged or jointed together, the entire armature being also hinged at its lower 40 end, as usual, whereby either end of the armature can be brought into connection with contact-points, as illustrated in the drawings and hereinafter described.

In the drawings, *A* represents a magnet of 45 ordinary construction and arranged in a main circuit, as usual. *a a'* are binding-posts for wires in such main circuit.

b b' are binding-posts for the wires of a local circuit.

50 *c* is a metal plate secured to the base *B*.

d is a yoke, the lower end of which is hinged at *r* to the plate *c*. This piece *d* is in fact a

part of the armature. *C* is the other part of the armature, the lower end of which is pivoted at *s* between the two arms of the yoke *d*, 55 as shown in Fig. 3.

D is a post secured to the base *B*.

E is a fork secured to the upper end of the post *D*. One of the arms *e* of this fork is provided with an adjustable contact-piece *f*, 60 which is made of rubber or other non-conducting material. The other arm *g* of this fork is provided with an adjustable metallic contact-piece *h*.

F is another fork, similar to the fork *E*, and 65 it is also secured to the post *D*. One arm *i* of this fork is provided with a contact-piece *j*, which is made of rubber or other non-conducting material, and the other arm of this fork *F* is provided with a metallic contact- 70 piece *l*.

m is an arm supported by the post *D*, and carrying at its outer end a screw *n*.

p is a coiled spring, one end of which is connected with the part *C* of the armature 75 near its lower end, and the other end of the spring is connected with the screw *n* in such manner that the tension of the spring can be adjusted by turning such screw. A wire passes from the lower end of the binding-post 80 *b* to the post *D*, and another wire from the plate *c* to the other binding-post *b'* of the local circuit.

The operation is as follows: Suppose the main circuit to be closed and the conditions 85 normal. The armature will be drawn toward the magnet, but its upper end will come in contact with the non-conducting contact-piece *f*, and the lower end, being held by the tension of the spring *p*, the same having been 90 properly adjusted, will be held in contact with the non-conducting contact-piece *j*, the armature thus being held away from the contact-points in the local circuit, as shown in Fig. 4. If from any cause the main line is 95 opened, the action of the magnet on the armature will cease, and the tension of the spring *p* will draw the armature over, and its upper end will come in contact with the contact-piece *h*, as shown in Fig. 1, and then the local 100 circuit will be completed through the binding-post *b*, the post *D*, the contact-piece *h*, the armature, the plate *c*, and post *b'*, the armature then being in the position shown in

Fig. 1. If from any cause the intensity of the current be materially increased, the action of the magnet will draw the armature into the position shown in Fig. 5, the upper end 5 of the armature then being in contact with the non-conducting piece *f* and the lower end being in contact with the metallic contact-piece *l*, the action of the magnet then overcoming the tension of the spring *p*, and the 10 armature being permitted to assume the position shown in Fig. 5 by reason of the two joints *r s*. In this position the local circuit will be completed through the binding-post *b*, post *D*, contact-piece *l*, the armature, the 15 plate *c*, and binding-post *b'*. When the parts are in the position shown in Fig. 4, the armature is held away from both of the metallic contact-points in the local circuit, which will then be inoperative. By means of this jointed 20 armature the upper end under certain conditions can be brought into contact with the non-conducting piece *f* and the lower end be at the same time in contact with the non-conducting piece *j*. Under other conditions the 25 upper end of the armature can be brought into contact with the metallic contact-piece *h*; and under still other conditions the upper end of the armature can be brought into contact with the non-conducting piece *f* and its 30 lower end into contact with the metallic contact-piece *l*, and by means of this jointed ar-

mature and a single magnet we are able to accomplish the desired result.

Our improvement can be used in connection with telegraphic fire-alarm apparatus, 35 with duplex telegraphic instruments, with printing-telegraphs, and with other electric apparatus.

We do not limit ourselves to the specific 40 way shown and described of hinging the two parts of the armature together, as they may be hinged together in various ways and at various points.

What we claim as new, and desire to secure 45 by Letters Patent, is—

An armature composed of two pieces, as *C d*, hinged together, the part *d* being also hinged at its lower end, in combination with a non-conducting contact-point *f*, so located that the upper end of the part *C* of the armature can be brought into contact with such contact-point *f*, and a non-conducting contact-point *j*, so located that the part *d* of the armature can come in contact with it, and two conducting contact-points *h l*, substantially 50 as and for the purposes specified.

CHAUNCEY D. BAKER.
LEWIE G. BRONSON.
